UNITED STATES PATENT OFFICE.

AQUILA DESCHAMBAULT, OF MARSHALL, MINNESOTA.

IRONING-BOARD.

SPECIFICATION forming part of Letters Patent No. 634,399, dated October 3, 1899.

Application filed March 14, 1898. Serial No. 674,138. (Model.)

To all whom it may concern:

Be it known that I, AQUILA DESCHAMBAULT, (having declared my intention to become a citizen of the United States,) residing at Marshall, in the county of Lyon and State of Minnesota, have invented certain new and useful Improvements in Ironing-Boards; and I do hereby declare the following to be a full, clear, and exact description of the invention, so as will enable others skilled in the art to which it appertains to make and use the same.

This invention relates to improvements in ironing-boards; and its object, among other things, is to provide a board which may be readily attached to or detached from a table or similar object and is produced with an attachment for supporting the ends or edges of the articles (that are being ironed) and prevent them from being soiled by coming in contact with the floor.

To these ends the invention consists in the novel construction and combination of parts hereinafter more fully described and claimed, and illustrated in the accompanying drawings, showing the preferred form of my invention, and in which—

Figure 1 is a perspective view showing the board in position and with the protecting device detached. Fig. 2 is a central section through the board and a portion of its leg. Fig. 3 is a top plan view showing the connection between the two portions of the leg. Fig. 4 is a side elevation showing the protecting device attached to said leg and having the end portions of its standard broken away. Fig. 5 is a detail perspective view of the protecting device detached. Fig. 6 is a top plan view of the standard of said protecting device with its cap removed.

Referring to said figures by letters of reference, A is the body of the board, slotted at one end, as at A', and provided upon its lower surface at either side of said slot A' with flanges a, having one or more perforations a', adapted to receive a pivot-pin b, passing through the upper portion B' of the leg B, which portion extends upward through said slot A'. The upper end of said portion B' is preferably provided with a head B², which has secured therein a strip of rubber, as b'. The portion B' extends downward and has its lower end bifurcated for some distance, as at

b², and provided with a band C, secured in any suitable manner to the portion B'. The slot b² of portion B' receives the upper end of the lower portion D of the leg, said end preferably inserted in a T-shaped casting D', the flanges d' of which bear against the upper and lower surfaces of the portion B', and thereby retain the end of portion D within the slot b². These flanges, with the band C, which, as is obvious, incloses the portion D when in position, prevent the said portion from tilting and retain it on a line with the upper portion B'. 65

In order to adjust the leg to a desired length, notches d are provided in portion D, either of said notches adapted to receive a pin C', secured to one end of a spring c, attached to said leg, said pin passing through the band C, as shown.

Near the lower end of the leg B is provided, preferably, a staple E, adapted to receive the toe f of a standard F, the lower end of which is beveled, so as to retain the same in a substantially vertical position when resting upon the leg B. The said end is preferably provided with a socket F', into which projects, when the standard is in position, a large staple G, secured to the leg B, as shown. The sides 80 of said socket F' are perforated, as at f', and a pin G' can be inserted therein, passing through the staple G, and thereby firmly retaining the standard F in position upon the leg. The upper end of the said standard is preferably 85 grooved, as shown in Fig. 6, said grooves f² receiving two wires or braces H, which are retained within the grooves f² by means of a cap F² and a screw f³ or any other suitable means. The ends of the braces are preferably 90 recurved, forming hooks H', which are adapted to engage with the four corners of a sheet or apron I, which is of greater width than the board, or at least extends horizontally beyond the edge of the board, and also extends beyond the free end thereof. As is obvious, the apron I will catch an overhanging portion of an article that is being ironed and prevent it from falling to the floor.

In attaching the board to the table the pivot-pin b is inserted into a pair of the perforations a' in the flanges a and into the leg therebetween. Said leg is then adjusted by withdrawing the pin C' from the notch d and

sliding the portion D of the leg upward or downward for the desired distance. The leg can then be locked by replacing the pin C in a notch d. It is obvious that the board 5 and its leg will pivot upon the pin b and serve to pinch or clamp the edge of the table or other object inserted beneath the bead B², and thereby become firmly attached thereto. The standard F is then placed upon the leg 10 and secured thereto in the manner described, whereupon the board and its attachment are in condition for use.

In the foregoing description I have shown the preferred form of my invention; but I do 15 not limit myself thereto, as I am aware that modifications can be made therein without departing from the spirit or sacrificing the advantages thereof, and I therefore reserve the right to make such changes as fairly fall 20 within the scope of my invention.

Having thus fully described my invention, what I claim as new, and desire to secure by Letters Patent, is—

1. In an ironing-board, the combination, with the leg thereof, of an attachment comprising a standard detachably secured to said leg, a series of braces attached to said standard, and an apron, substantially as described. 25

2. In an ironing-board, the combination with the leg thereof, of an attachment consisting of a detachable standard, arms extending from said standard, and an apron detachably secured to said arms, substantially as described. 30

3. In an ironing-board, the combination with the leg thereof and the staples thereon, of an attachment consisting of a standard having a toe adapted to project into one of said staples, the second staple on said leg adapted to project into said standard, and means for 40 securing said standard to the staple, substantially as described. 35

AQUILA DESCHAMBAULT.
